H. R. PATTERSON

IGNITION SYSTEM

Filed Aug. 28, 1919

INVENTOR.
Harry R. Patterson.
BY Chester W. Braselton
ATTORNEY

UNITED STATES PATENT OFFICE.

HARRY R. PATTERSON, OF TOLEDO, OHIO, ASSIGNOR TO ELECTRIC AUTO-LITE CORPORATION, OF TOLEDO, OHIO, A CORPORATION OF DELAWARE.

IGNITION SYSTEM.

Application filed August 28, 1919. Serial No. 320,374.

To all whom it may concern:

Be it known that I, HARRY R. PATTERSON, a citizen of the United States, residing at Toledo, in the county of Lucas and State of Ohio, have invented certain new and useful Improvements in Ignition Systems, of which I declare the following to be a full, clear, and exact description.

This invention relates to electric lighting and power plants employing an internal combustion engine which drives an electric generator to charge a storage battery. It relates particularly to the manner of stopping the engine when the battery has been charged to the desired amount.

An object of my invention is the provision of means for stopping the engine after a definite quantity of electricity has been put into the battery by rendering the ignition mechanism ineffective.

Another object is the provision in such a system of means whereby when the charge is complete the charging circuit is not opened while the charging current has an appreciable value but only after it has reduced to a small or negligible value.

Further objects of this invention will appear from the detailed description to follow. I accomplish the objects of my invention in certain instances by the devices and means described in the following specifications, but it is evident that the same may be varied widely without departing from the scope of the invention, as pointed out in the appended claims. Arrangements constituting certain embodiments of my invention, any one of which may be the preferred, are illustrated in the accompanying drawings forming a part thereof, in which:

Figure I is a circuit diagram illustrating one form of my invention.

Fig. II is a fragmentary circuit diagram illustrating a modification.

Fig. III is another fragmentary circuit diagram illustrating a further modification.

In the drawings, similar reference numerals refer to similar parts throughout the several views.

A prime mover consisting of an internal combustion engine 5 is shown direct connected to a shunt wound generator 6 by a shaft 7. This generator has a shunt winding 8 and a third brush 9 from which the ignition current for the engine is taken.

Its main brushes are connected to circuit

wires 10, 10' for charging a storage battery 11 or for supplying current to translating devices such for example as lamps 12 or a motor 13. In the connection 10' between the generator and the battery is an electromagnetic switch or cut out 15 having a potential winding 16 and a current winding 17 so connected that they act cumulatively when the battery is being charged. A hand lever 18 is employed to manually close the switch for starting the engine.

The ignition system comprises the usual cam driven interrupter and induction coil. According to the drawing the engine shaft 7 carries a pinion 20 meshing with a gear 21 on the cam shaft 22. The cam 23 operates an interrupter lever 24 which, cooperating with a stationary contact 25, serves to open and close the primary circuit 27. This circuit includes the primary winding 28 of induction coil 29 and is connected to the third brush 9 of the generator. The secondary 30 connects as usual with the spark plug 31 of the engine.

Ignition apparatus such as that just described is usually designed to provide the necessary spark for firing the engine only when a suitable condenser is connected across the interrupter contacts. According to my invention I also employ a condenser in this manner, but provide means for rendering the condenser ineffective when it is desired to stop the engine. The condenser 33 has one terminal connected to the stationary contact 25 while its opposite terminal is connected through the back contact 34 and armature 35 of a relay 36 to ground and thereby to the moving contact on the interrupter lever 24. The winding 37 of this relay has one end 38 connected to the wire 10 while its other end 39 connects with a moving contact 40 of an ampere hour meter 41. This meter 41 is connected in series with the battery and may indicate the amount of electricity put into or taken from the battery. A grounded stationary contact 42 is adapted to be engaged by the moving contact 40 when the battery is fully charged.

In operation let it be assumed that the parts are as shown in Fig. 1 and that the battery is being charged. When full charge is reached, the contact 40 of the ampere hour meter will touch the contact 42 thereby energizing relay 36 to open the circuit of condenser 33. With the effect of the condenser

removed the ignition spark ceases and the engine gradually comes to rest. However as soon as its speed has decreased to the point where the generator E. M. F. equals that of the battery or is slightly less permitting a reverse current the cut out 15 operates to open the charging circuit and prevent further discharge. In starting the engine the generator is operated as a motor taking energy from the battery, the hand lever 18 being operated to close the circuit.

According to the modification illustrated by Fig. II the relay 36, which is connected to the ampere hour meter as in Fig. 1, serves 15 to short circuit the condenser as well as the interrupter. The condenser 33 in this case is permanently grounded at one terminal but has its other terminal, which is connected with the contact 25, connected also with the 20 front contact 45 of the relay 36. When the relay is energized both the condenser and the interrupter are short circuited.

According to the modification illustrated by Fig. III the condenser and interrupter 25 are short circuited as in the previously described modification but in this case the relay 36 is dispensed with the moving contact 40 of the ampere hour meter being connected with the condenser and interrupter. 30 In operation the ampere hour meter closes directly the short circuit path about the condenser and interrupter.

While I have described my invention in more or less detail and as being embodied 35 in certain precise forms I do not desire or intend to be limited thereto, as on the contrary my invention contemplates broadly all proper changes, as well as the omission of immaterial elements and the substitution of 40 equivalents therefor, as circumstances may suggest or necessity render expedient.

Having thus described my invention, what I claim as new and desire to secure by Letters Patent, is:

45 1. In a battery charging system comprising an internal combustion engine having an ignition circuit including an interrupter and a condenser connected across the interrupter contacts, a generator and a storage 50 battery, the method of controlling the amount of charge given to said battery which consists in integrating the current delivered to said battery and when its in-

tegrated value reaches a predetermined amount of successively rendering said condenser and interrupter ineffective. 55

2. In a battery charging system comprising an internal combustion engine having an ignition circuit including an interrupter and a condenser connected across the interrupter contacts, a generator and a storage battery, the method of controlling the amount of charge given to said battery which consists in opening the condenser circuit and subsequently opening the charging 60 circuit when the potential of the generator becomes equal to or slightly less than the potential of the battery. 65

3. In combination an internal combustion engine, an ignition system therefor including an interrupter and a condenser connected thereto, a generator operatively connected to said engine, a storage battery adapted to be charged by said generator and means including an ampere hour meter in 70 circuit with said battery for opening the circuit of said condenser. 75

4. In combination an internal combustion engine, an ignition system therefor including an interrupter having a condenser connected thereto, a generator adapted to be driven by said engine, a storage battery connected to be charged by said generator, a switch in the circuit connections of said condenser and means responsive to the integrated current received by said battery for 80 operating said switch. 85

5. In combination an internal combustion engine, an ignition system therefor including an interrupter having a condenser connected across the contacts thereof, a generator adapted to be driven by said engine, a storage battery connected to be charged by said generator, a translating device connected to said battery, a switch in the circuit connections of said condenser, an electromagnet for operating said switch and an ampere hour meter in circuit with said battery having a switch in circuit with said electromagnet whereby the ampere hour 90 meter may control the ignition circuit to 95 stop the engine. 100

In testimony whereof, I affix my signature.

HARRY R. PATTERSON.
